UNITED STATES PATENT OFFICE

2,008,341

HIGH TENSION INSULATOR

Charles L. Stroup, Huntington, W. Va., assignor
to Jeffery Dewitt Insulator Company, Kenova,
W. Va., a corporation of West Virginia

Application May 26, 1933, Serial No. 673,093

6 Claims. (Cl. 173—318)

This invention is an insulator of the high tension type.

In Letters Patent 1,851,671 issued to Robert M. Johnston et al. on March 29, 1932, is illustrated and described a high tension insulator comprising a dielectric body having an axially disposed chamber constructed and arranged to receive a suspension pin. Said pin is anchored within the chamber by means of a suitable metal, preferably one which is capable of being applied while in a molten condition, said metal possessing the necessary mechanical strength to firmly unite the dielectric body and the pin, in such manner as to resist all normal strains tending to separate them. As shown in the drawing of the patent, the exposed surface of the alloy is covered to a substantial depth by a waterproofing material. In practical operation, however, it has been found that there is a concentration of electrostatic field at the end surface of the metal closest to the air, which condition has a tendency to produce a concentration of dielectric stress, and also tends to reduce the puncture voltage of the insulator.

One of the objects of the present invention is to provide an insulator of the type above described constructed and arranged to prevent the concentration of dielectric stress at the metal surface, and thereby very materially raise the puncture voltage and uniformity of the insulator structure. A further object is to accomplish the desired results by providing a covering material for the metal which has what may be termed "a grading effect" or the characteristic of variable conductivity from the metal to the air, reliance being placed upon the metal for mechanical strength, the covering material being utilized purely because of its effect upon the electrical functions.

The invention will be hereinafter fully set forth and particularly pointed out in the claims.

In the accompanying drawing, the figure is a side elevation, partly in section, illustrating an insulator constructed in accordance with the invention.

Referring to the drawing, I designate an insulator of suitable dielectric material, such as porcelain for instance, provided with a hub-like portion 11 of any desired contour. A flange or petticoat 12 is formed integrally with the hub-like portion, and provided with depending annular ribs 13 to increase the leakage and flash over distances. The dielectric body thus far described may be of any desired conformation, the design shown in the drawing having been selected for illustrative purposes only, and without intent to limit the invention. The body of the insulator is provided with a central axially disposed chamber 14, open to the air at the lower

end as illustrated in the drawing, the open end being slightly flared.

The hub-like portion 11 is enclosed within a correspondingly shaped metal cap 15, preferably of pressed steel. This cap may be secured to the hub in any suitable or desired manner, but for purposes of illustration it is shown as connected to the dielectric material in the manner described in the above identified patent. For instance, the cap 15 is shown as being of somewhat larger diameter than that of the hub 11, so as to provide a substantial space between them, said space being filled by an asphaltum waterproofing material indicated at 16. The cap is also shown as slightly flared at its lower edge, as indicated at 17, and provided with an inwardly extended annular flange 18. Interposed between the mouth portion of the cap and the adjacent portion of the dielectric body, and interlocking with the flange 18, is a metallic anchorage 19, preferably consisting of a metal capable of being applied while in a molten condition. The features thus far described are shown in the Johnston et al. patent above identified, and are not claimed in this application.

The central chamber 14 is illustrated as provided with a suitably roughened wall portion at the inner end thereof, preferably in the form of screw threads or corrugations 20, and the suspension pin 21 is provided with similar corrugations 22, in the form of a screw thread. The inner end of the pin 21 bears against a resilient washer 23, such as cork or the like interposed between said end and the inner end wall of the recess 14. Said pin is anchored to the interior of the chamber 14 by means of a metal thimble 24, preferably made of a metal capable of being applied while in a molten condition. This metal is preferably zinc or zinc alloy because it may be poured into the space between the pin 21 and the adjacent wall of the recess, and possesses the characteristic that it will shrink slightly upon cooling. It will be noted that the metal fills the spaces between the corrugations 20 and the screw threads 22, and provides an absolutely firm and strong anchorage for the pin, possessing great mechanical strength.

The anchorage 24, while in position presents an annular ring-like outer or lower end surface which would normally be exposed to the atmosphere and if not properly covered is the cause of a very strong concentration of the electrostatic field at the exposed surface. Therefore, some material must be provided to cover this surface, in such manner as to provide a grading effect of electric conductivity, which will prevent concentration of said dielectric stress at the alloy surface. The waterproof covering employed in the Johnston et al. patent, above identified will not perform this function. However, it has been

found that if the normally exposed metal surface is covered to a substantial depth by a body of cement as indicated at 25, very marked change in this condition is effected, and the concentration of the dielectric stress is approximately prevented. Cement is known to be relatively dry at the surface which is exposed to the air, but is somewhat damp at the portion next to the metal. It has been demonstrated that this hygroscopic condition produces a remarkable grading effect upon the electric conductivity from the metal to the air, which prevents the concentration of the dielectric stress at the alloy surface, and as an important result, it very materially raises the puncture voltage and uniformity of the insulator as a whole. It is of decided advantage in suspension insulators employing metallic alloy as the means of carrying the mechanical stresses. In practice it is preferred to interpose an asphaltum waterproofing compound between the longitudinal wall of the recess and the grading material 25, and also to cover the exposed outer end surface of said grading material in a similar manner. Said waterproofing material is indicated at 26.

It is preferred to use neat Portland cement as the grading material, but other substances of graded conductivity may be employed, such as any hydraulic cement either neat, or admixed with sand, iron filings, or semi-conducting substances, such as carborundum dust. Among other cements may be mentioned litharge-glycerine, plaster of Paris, and lime. Any of these substances will function to grade the electro conductivity from a maximum at the outer end of the metal to a minimum at the outer end of the grading material, where the latter contacts with the air.

The advantages of the invention will be readily understood by those skilled in the art to which it belongs. For instance, the value of an insulator is known to depend upon its ability to withstand puncture under the stresses of carrying the high voltage current. By employing a suitable material for grading the conductivity from the metal to the air, a most important result is obtained, in that by preventing the concentration of the dielectric stress at the metal surface, the puncture voltage of the insulator, as well as the uniformity of its insulating functions, are very materially improved.

Having thus explained the nature of the invention and described an operative manner of constructing and using the same, although without attempting to set forth all of the forms in which it may be made, or all of the forms of its use, what is claimed is:—

1. An insulator of the character described comprising a dielectric body having a central axially disposed recess, a pin having a portion extended into said recess, a metallic anchorage material constructed and arranged to retain said pin in said recess, and a covering of variable electroconductivity interposed between said metallic anchorage material and the air in such manner as to prevent the formation of a concentrated electrostatic field at the outer surface of said metal.

2. An insulator of the character described comprising a dielectric body having an axially disposed central recess, a pin of less diameter than the recess and having a portion extended longitudinally thereinto, a metallic anchorage filling the space between a portion of said pin and an adjacent portion of the longitudinal wall of said

recess, and a body of material of variable electroconductivity filling the space between another portion of the pin and an adjacent portion of the longitudinal wall of the recess, and covering the outer surface of said metallic anchorage in such manner as to prevent formation of a concentrated electrostatic field in the vicinity of said metallic anchorage.

3. An insulator of the character described comprising a dielectric body having a central axially disposed recess, the inner portion of the longitudinal wall of said recess being roughened, a suspension pin having a portion extended into said recess, said extended portion being roughened at a locality adjacent to the roughened portion of said recess, said pin being of less diameter than the recess, a metallic anchorage material filling the space between the pin and the wall of the recess and constructed and arranged to interlock with said roughened portions and firmly anchor the pin to the dielectric body, and a material of variable electric conductivity covering said metallic anchorage material and interposed between the same and the air, said material being constructed and arranged to prevent formation of a concentrated electrostatic field at the surface of the alloy.

4. An insulator of the character described comprising a dielectric body having a central recess, a pin having a portion extended into said recess, a metallic anchorage material interposed between said pin and the adjacent longitudinal wall of said recess, and constructed and arranged to retain said pin in said recess, a covering interposed between the outer end of said metallic anchorage material and the air, said covering being of variable conductivity and constructed and arranged to prevent the formation of a concentrated electrostatic field at the surface of said metal, a waterproofing material interposed between said grading material and the adjacent longitudinal wall of said recess, and a similar waterproofing material covering the outer end of said grading material.

5. An insulator of the character described comprising a dielectric body having a central axially disposed recess, a pin having a portion extended into said recess, a metallic anchorage interposed between adjacent portions of the pin and the wall of the recess and constructed and arranged to firmly connect the pin with said dielectric body, and the body of cement interposed between the lower edge of said metallic anchorage means and the air, said cement being constructed and arranged to prevent concentration of electrostatic field at the surface of the alloy.

6. An insulator of the character described comprising a dielectric body having a central axially disposed recess, a pin having a portion extended into said recess longitudinally and of less diameter than the recess, a thimble-like metallic anchorage interposed between said pin and the adjacent wall portion of said recess, said anchorage being constructed of a metal capable of being applied while in a molten state, said thimble having an annular outer edge portion, and a body of cement located in the lower portion of said recess and so positioned as to engage and cover said annular outer edge of the metal anchorage, said cement being constructed and arranged to prevent concentration of electrostatic field at said annular edge.

CHARLES L. STROUP.
